WITNESS:

ATTORNEY

UNITED STATES PATENT OFFICE.

PRICE ALDERFER, OF SOUDERTON, AND THOMAS F. CLEMENTS, OF PHILADELPHIA,
PENNSYLVANIA.

WINDOW CONSTRUCTION.

Application filed March 13, 1923. Serial No. 624,774.

To all whom it may concern:

Be it known that we, PRICE ALDERFER and THOMAS F. CLEMENTS, citizens of the United States, residing at Souderton and Philadelphia, in the counties of Montgomery and Philadelphia and State of Pennsylvania, have invented new and useful Improvements in Window Constructions, of which the following is a specification.

10 This invention relates to window construction, and particularly to windows adapted for use in bathrooms and porch enclosures. One of the principal objects is to construct a device of this nature which shall be cheap 15 to construct and install, which will avoid the use of weights and springs, will permit of varying degrees of ventilation from side and top and bottom, and will be readily held in any desired position.

20 Another object is to provide a window which will serve the double purpose of closure and awning.

Another object is to produce a device of this nature which is particularly adapted to 25 ventilate a bathroom and at the same time provides the maximum of privacy.

Another object is to produce a novel lock for such devices.

Another object is to provide a lock which 30 shall be automatically operated by the manipulating devices for manipulating the sash elements.

With these and other objects in view as 35 will be more apparent, the invention consists in certain novel constructions and combinations and arrangements of parts, the essential features of which are hereinafter fully described, are particularly pointed out in the appended claim, and are illustrated in 40 the accompanying drawing, in which:

Figure 1 is a view of a window frame fitted with our improvements and with one side removed to show the hardware and operating parts.

45 Figure 2 is a detail view showing the upper bracket.

Figure 3 is a detail of the lug-carrying plate co-operative with the bracket of Figure 2.

50 Figure 4 is a detail of the frame to show the securing plate.

Figure 5 is a detail showing one of the window locks.

Figure 6 is a sectional view of one of the locks. 55

Figure 7 is a detail perspective view of a lug carrying plate used in the construction.

Like characters of reference refer to like parts in all the views.

Referring to the drawing in detail, 10 60 represents the window frame, the jambs of which are formed with tracks, race-ways or runs 11 extending from top to bottom and provided with notches or rests 12 which may be arranged at convenient distances apart. 65 The upper and lower sashes are indicated respectively at 13 and 14, and are joined at the side edges by hinges 15 which fit in flush with the edges of the sashes.

Secured at each side of the lower end of 70 the lower sash 14 is a plate 16 carrying an outstanding lug 17 which enters and travels in the run or race-way 11 of the respective adjacent jamb. The lugs 17 may travel up and down in the races 11 upon moving 75 the sashes relatively on their hinges, and by stopping the lugs in any one of the rests 12, the window may be maintained at a conveniently open position, and by proper manipulation, the lower sash may be so positioned that the outside of it is readily 80 reachable from the interior of the room making it easy to clean the outside of the glass in this sash. It will also be seen that if a shade is placed on the upper sash 13, this 85 sash may be raised into a position in which it will perform the functions of an awning.

At the upper outer faces of the upper sash 13 there are arranged plates 18 having outstanding lugs 19 which are also capable of 90 movement along the race-ways 11 and capable of being rested in any one of the rests 12. This construction permits the lowering of the upper sash so as to form an upper opening for ventilating purposes, and if the 95 sash be brought down far enough, it can conveniently be reached from inside the room for cleaning the outside of the glass in this sash.

The lower end of the runway 11 is provided with an inwardly extending off-set at 100 20 so that when the lower sash 14 is brought completely down, this sash will be forced tightly against the stop 21. The upper end of each run 11 is finished off by merging into 105 a slot in a plate 22 set into the window frame

and extending outwardly therefrom. The plate 22 is provided with two shoulders, shown respectively at 23 and 24. In normal condition with the window entirely closed, the lugs 19 rest on the shoulders 23. In lowering the upper sash, the lugs 19 may be rested against the shoulders 24 when it is desired to have only a limited amount of ventilation.

10 The means for holding the sashes closed and for manipulating the lower sash comprises a pair of locks which are identical in construction and operation except that one is "right-hand" and the other "left-hand".
15 This means comprises a special lock, the frame of which is indicated at 25 and may be of any suitable size and shape to hold the working parts hereinafter described. Inside the frame and pivoted on trunnions 20 26 extending into the frame 25 is a bar 27 which carries a latch or hook 28 and a handle 29. The latch 28 projects through an aperture in the plate or frame 25 and is adapted to engage with a catch plate 30 secured on the stop. A spring 32 constantly presses on a finger 31 of the bar 27 so as to turn the latch or hook 28 into locking position. The handle 29 also projects through the frame 25, and when grasped and lifted 25 up on, causes the latch or hook 28 to be disengaged from the catch plate 30.
30 If desired, locks may be secured on both

sashes, but it is much cheaper construction to place only a grip member 33 on the upper sash to manipulate it with.

35 While we have described what we deem to be the most desirable embodiment of our invention, it is obvious that many of the parts may be varied without in any way departing from the spirit of our invention, and we therefore do not limit ourselves to the exact details of construction herein shown nor to anything less than the whole of our invention limited only by the appended claim.

40 What we claim is:—

45 In a window construction, the combination with a window frame formed with run-ways, plates at the top of said frame having slots 50 communicating with the upper end of the run-ways, the slots in said plates curving outwardly away from the run-way and terminating at their upper end in a tapered shoulder, having an outwardly positioned depressed shoulder at their lower ends, hingedly connected sashes, and lugs on each of 55 said sashes and movable in said run-ways, the lugs on the upper one of said sashes adapted to move in the slots in the plates and into the shoulder therein.

60 In testimony whereof we affix our signatures.

PRICE ALDERFER.
THOMAS F. CLEMENTS.
